J. E. GROSJEAN

HEEL FOR BOOTS AND SHOES

Filed Dec. 9, 1924

Inventor
James E. Grosjean,

James L. Morris

UNITED STATES PATENT OFFICE.

JAMES E. GROSJEAN, OF LIMA, OHIO.

HEEL FOR BOOTS AND SHOES.

Application filed December 9, 1924. Serial No. 754,783.

The present invention relates to improvements in heels for boots and shoes, and more particularly to those of the class embodying textile or fibrous material and rubber in their composition.

The primary object of this invention is to provide a novel and improved heel made from scraps or trimmings of cord and fabric tire stock which have been heretofore discarded or sold as waste by rubber tire manufacturers, and which, if reclaimed, required destroying the cord threads of textile material to enable reclaiming of the rubber friction. Such recovery processes, therefore, destroyed the essential elements I propose using in making the improved heel, as the textile material contained by such is capable of affording the highest wearing qualities and true non-slip properties, and the present invention enables such waste or by-product to be utilized in the production of heels which possess advantages not possessed in heels as heretofore constructed and produced from other materials.

Novel and improved heels of this class comprise a tread-forming body composed of textile cords, threads or fibers which are bonded or vulcanized together with rubber and most of which are laid or strewn in the same direction in such body and so that the ends of such cords, threads or fibers are presented to the wear surface of the heel. A superposed body composed of textile cords, threads or fibers which also are bonded or vulcanized together with rubber, and most of which are laid or strewn in the same direction in such body so that they extend substantially parallel to the wear surface of the heel may be employed in addition to the tread-forming body, the two bodies being vulcanized together. A heel constructed in this way will possess great wear-resisting properties, due to the presentation of the ends of the cords, threads or fibers of the tread-forming body to the wear surface of the heel, and when the superposed body is employed, the heel may be readily and securely attached to the boot or shoe by nails which may be driven at any suitable or desired points through the lower and superposed bodies so that the heads of the nails lie against the under side of the superposed body, the nail heads being presented to the sides of the cords, threads or fibers of the superposed body, and, hence, strains tending

to pull the heel from the boot or shoe will act transversely of the lengths of such cords, threads or fibers, and such strains will be thus effectively resisted thereby.

Another object of the invention is to provide a heel of this kind which will possess cushioning properties, for which purpose, the upper side of the heel is formed with a cavity which permits the portion of the heel within its periphery to yield, and thus afford comfort and avoid shock to the wearer.

A further object of this invention is to provide a heel having a true non-slip wear surface, the same being produced by the use of cord threads intermixed with frictioned rubber, the cord threads being presented to the wear surface throughout the entire area of the heel, the ends of the cotton twisted cords constituting one of the best known non-slip materials, and all the cords or threads being bonded or vulcanized together with rubber, the heel thus produced providing sure footing and safety to the wearer on wet and icy sidewalks.

To these and other ends the invention consists in certain improvements and combinations and arrangements of parts, all as will be hereinafter more fully described, the features of novelty being pointed out particularly in the claims at the end of the specification.

In the accompanying drawing:—

Figure 1 is a bottom plan view of a heel constructed in accordance with the present invention, this figure showing the preferred form of the tread surface thereof;

Figure 2 is a top plan view of the heel;

Figure 3 represents a longitudinal section through the heel, taken on the line 3—3 of Figure 1;

Figure 4 represents a transverse section through the heel taken on the line 4—4 of Figure 1;

Figure 5 is a perspective view of the heel as viewed from its under side, this figure showing a portion of the margin of the heel detached to more clearly illustrate the construction;

Figure 6 is a view similar to Figure 3 showing the invention applied to a half heel;

Figure 7 is a view similar to Figure 4, also showing the invention applied to a half heel; and

Figure 8 is a bottom plan view of the heel as shown in Figures 6 and 7, this figure

2
illustrating another form of tread surface that may be used.

Similar parts are designated by the same reference characters in the several views.

5 The present invention is applicable to either whole or half heels and such heels may be used upon the various classes of boots and shoes, such, for example, as sport, golf and workmen's boots and shoes where 10 great wear-resisting properties are desirable, athletic shoes where resilience, pliability and non-slipping properties are desired, or shoes for ordinary wear wherein some or all of these properties are desirable. The preferred embodiment of the invention are 15 shown in the accompanying drawing and will be hereinafter described in detail. It will be understood, however, that the invention is not restricted to the precise embodiments shown, as equivalent structures are 20 contemplated, and such will be included within the scope of the claims.

The heel, according to the present embodiment of the invention comprises a lower 25 tread portion or body, designated 1 in Figures 3, 4 and 5, and 1^a in Figures 6 and 7, and a superposed or upper body, designated 2 in Figures 3, 4 and 5, and 2^a in Figures 6 and 7. These two bodies comprising the 30 major portion of the heel are each composed of a material which consists of textile cords, threads or fibers, most of which are arranged in the same direction in such material, and the cords, threads or fibres are impregnated 35 with and covered by a vulcanizable substance, preferably "friction", such as is used in the cord tire industry for vulcanizing together the plies of cords or fabrics in tires. This material is preferably prepared sub- 40 stantially in the manner set forth fully in my prior application Serial No. 722,552, filed June 26, 1924, reference being made to that application for a detailed description of the preferred method of preparing the material. 45 It may be briefly stated, however, that this material is prepared preferably from remnants or scraps of cord or fabric tire material such as is produced in the tire man- 50 ufacturing industry by trimming the cord or fabric stock applied to the tire molds. This cord or fabric stock is usually gum dipped and impregnated with the highest quality of so-called "friction" which is the highest 55 grade rubber cement in an uncured condition, and also the cord or fabric stock is fric- 60 tioned and skim-coated with a high grade of uncured rubber. Masses of scraps or trim- 65 mings of such cord or fabric material, which are ordinarily waste material in tire man- 70 ufacturing plants, are first passed through a cracker such as that used in tire factories, after which the material is passed through a mill having smooth-faced rolls, the effect of 75 the passage of the material through the cracker and the mill being to re-arrange the

80 promiscuously extending cords, threads or fibers so that they all, or the most of them, extend in substantially the same direction. Where woven fabric stock is used in the preparation of this material, the passage of 70 the same through the cracker serves to break up the fabric formation and to re-arrange the cords or threads so that most, if not all, of them extend in the same direction. The material thus prepared may then be forced 75 through a so-called tube machine, such as that commonly used in plants producing rubber products, thus producing a strip of material which has a cross-section corresponding substantially with the outline of 80 the heel in plan, this strip of material having the cords, threads or fibers extending longitudinally thereof. Sections of the strip may be cut off to form the tread bodies 1 or 1^a, the cutting of these bodies from the strip being on lines transverse to the lengths of the cords, threads or fibers. The upper or superposed bodies 2 or 2^a when used to make up part of the depth of the heel may be formed directly from the sheet of material 90 as it comes from the smooth-faced rolls, the cords, threads or fibers in such sheet extending substantially parallel with the two surfaces of the sheet in the embodiment herein shown. 95

100 It will be understood that most, if not all of the cords, threads or fibers, designated 3 in Figures 3, 4 and 5, and 3^a in Figures 6 and 7, extend perpendicularly or substantially so with respect to the tread surface 4 or 4^a of the heel. The cords, threads, or fibers 5 in the superposed body as shown in Figures 3, 4 and 5 or 5^a in Figures 6 and 7 extend parallel or substantially so with respect to the tread surface 4 or 4^a. The 105 cords, threads or fibers in both bodies, as previously stated, are impregnated and mixed with uncured "friction" and high grade rubber which was used as a skim-coat- 110 ing in the scraps or trimmings from which the material was prepared. The two bodies, 1 and 2, or 1^a and 2^a, after having been cut to the appropriate size and shape, are super- 115 posed and a margin 6 or 6^a, composed prefer- ably of a rubber compound similar to that generally used in the making of ordinary 120 rubber heels, is placed around the circumference of the superposed bodies 1 and 2 or 1^a and 2^a. The whole is then placed in a mold and cured, as is usually done in the man- 125 ufacture of rubber heels. This curing operation vulcanizes the "friction" and rubber which impregnates and is mixed with the cords, threads or fibers of the bodies 1 and 2 or 1^a and 2^a, thereby securely bonding together these fibers and producing a material which possesses great wear-resisting prop- 130 erties. Furthermore, the curing operation vulcanizes together the bodies 1 and 2 or 1^a and 2^a, thus securely uniting them. In addi-

tion, the marginal strip 6 or 6^a is vulcanized and it is firmly united with the remainder of the heel composed of the bodies 1 and 2 or 1^a and 2^a.

- 5 The tread of the heel may be plain or flat, or it may be formed with cleats 7, as shown in Figure 1, heels of this type being particularly suitable for use on athletic shoes as a tread of this character with cord threads 10 intermingled in the body of the heel will resist slipping, even on wet grass, or the tread may be formed with a series of annular downwardly projecting ribs 8 which may be formed concentrically with nail-receiving 15 holes 9.

In either embodiment of the invention, the heel may be readily and securely attached to the boot or shoe by driving a suitable number of nails 10 upwardly through the lower 20 body 1 or 1^a and through the superposed or upper body 2 or 2^a so that they enter and may be clinched in the shoe, the nails being driven until their heads 10^a come against the under side of the superposed or upper body 25 2 or 2^a. By arranging the cords, threads or fibers in this superposed or upper body 1 or 1^a, whereby they extend parallel or substantially so with respect to the tread surface of the heel, the nail heads will engage the cords, 30 threads or fibers of the superposed body 2 or 2^a in a direction transversely of the length of these cords, threads or fibers, the latter thereby offering increased resistance to the driving of the nails which will indicate 35 to the workman that the nails have been driven to the proper depth, and, moreover, this increased resistance offered by the cords, threads or fibers of the superposed body and which extend transversely of the nails, affords a very secure anchorage for the nail 40 heads which will prevent pulling of the nail heads through the superposed body under strains to which the heel is subjected while in use. It will be understood that any desired 45 number of nails may be driven to secure each heel, and that these nails may be driven simultaneously or otherwise and at any desired points, although in the form of tread shown in Figure 8, the nails would be 50 driven in the holes 9 formed in the centers of the annular projecting ribs 8.

The present invention also provides means for affording cushioning properties to the heel whereby the portion of the heel within 5 its margin may yield under the weight of the foot of the wearer, thus increasing the comfort of the wearer and affording other advantages. As shown in Figures 2, 3 and 4, this cushioning effect may be obtained by 10 deforming the superposed body 2 from a flat shape so as to form grooves or recesses 11 and 12 in its upper surface, leaving a projection 13. This deforming of the superposed body 2 may be effected during curing 15 of the heel, by appropriately shaping the

mold in which the heel is cured. When the heel is applied to the sole 14 of the boot or shoe, the central portion, as well as the projection 13 of the heel, will be normally offset below the lower side of the sole 14, but pressure exerted on the heel due to the weight of the foot thereon will cause the portion of the heel within its margin to yield more or less in an upward direction or toward the under side of the sole 14, due to the recessing of the 70 upper side of the heel which forms a cavity between it and the sole 14. The projection 13 will come into engagement with the sole 14 when sufficient pressure is applied to the heel, thereby preventing undue distortion 75 of the heel. A similar cushion is shown in Figures 6 and 7 wherein the portion of the superposed body 2^a within its margin is depressed or offset downwardly to form a recess 15 and a projection 16 is formed within this recess, the recessed portion of the heel permitting it to yield upwardly under the weight imposed thereon, and the projection 16 being arranged to abut against the heel lift 17 above it and thereby limit the amount 80 of yield which will take place, thereby avoiding 85 undue distortion of the heel.

As shown in Figs. 3 and 4, the center of the tread surface of the heel may be arched, as indicated at 18. This arching enables the 90 center of the heel to yield due to the hollow space above it, and said space being arched over with the cord fabric and rubber cured in that position. This arched portion of the heel will rebound when released from pressure and will produce more cushioning action, and the heel will not wear as rapidly in the center as it would if solid. Eventually, due to wear, the center of the heel 95 will project or arch further below the edge 100 of the heel and will produce more cushioning action when nearly worn out than when the heel was new.

The material composing the tread-forming body of the heel and also the superposed body when used consists mainly of textile cords, threads or fibers, there being sufficient "friction" or rubber, however, to impregnate these cords, threads or fibers and thus render them tough and waterproof and to securely bind these cords, threads or fibers together. The material, when cured or vulcanized, in consequence, possesses great toughness, strength and wear-resisting and non-slip properties. The relatively short length 110 of loose or unwoven fibers or threads lying in the highly elastic friction do not impair the resilience of the latter, especially as these fibers or threads are gum-dipped or friction-impregnated, which renders them also resilient, and, hence, the tread-forming body of the heel provides a highly resilient cushion. By arranging the cords, threads or fibers in the tread-forming body so that 115 they are presented endwise to the tread 120 125 130

surface of the heel, the maximum wear-resisting properties of the material are utilized, and by arranging the cords, threads or fibers in the upper or superposed body, when used, so that they extend substantially parallel to the plane of the tread surface, secure anchorages for the attaching nails are provided which are capable of sustaining forces tending to pull the nail heads through the upper portion of the heel. Owing to the large proportion of textile material composing the heel, the weight of the heel is substantially less than that of the usual rubber heels, and in consequence they will be more comfortable, and they will cause less fatigue to the wearer.

I claim as my invention:—

1. A heel for boots and shoes comprising a tread-forming body made from re-claimed uncured tire material and composed of loose

textile fibers and friction, most of the fibers extending in the same direction in said body and presenting their ends to the tread surface thereof, the friction being vulcanized and thus uniting the fibers elastically.

2. A heel for boots and shoes comprising a tread-forming body composed of unwoven textile fibers and high-grade highly elastic rubber, the fibers being distributed loosely through the body but extending mostly in the same direction therein and presenting their ends to the tread surface of the body, the fibers being bonded together elastically by the vulcanized rubber comprised in said body.

3. A heel for boots and shoes comprising a tread-forming body composed of unwoven gum-dipped textile threads and high-grade friction, the textile threads being distributed loosely in the body and extending mostly in the same direction therein and united elastically by said friction in the body whereby the fibers may accommodate themselves to compression of the body in the direction of the length of the fibers, the fibers pre-

senting their ends to the tread surface of the body.

4. A heel for boots and shoes comprising a lower tread-forming body and another body superposed thereon, each of said bodies being composed of unwoven textile threads distributed loosely through the respective body and extending mostly in the same direction therein and high-grade, highly elastic friction bonding together the threads in each body, the tread-forming body having a tread surface formed by the ends of the threads and the friction composing it, the threads in the tread-forming body being elastically connected by the friction therein and thus rendered capable of free movement relatively to one another to conform with compression of said body in the direction of the length of the threads by force applied to the tread surface.

5. A heel for boots and shoes comprising a body composed of gum-dipped frictioned unwoven textile fibers most of which extend in the same direction and are vulcanized together, said body having a tread surface the center of which tread surface is arched downwardly to produce a cushioning portion having a cavity above it.

6. A heel for boots and shoes comprising superposed bodies each composed of gum-dipped frictioned unwoven textile fibers most of which extend in the same direction in the respective bodies and are vulcanized together, one of said bodies forming a tread surface to which the fibers in said body are presented endwise, and the central portions of said bodies being arched downwardly, thus forming a cavity above such downwardly-arched portion and producing a cushioning action in said downwardly-arched portion.

In testimony whereof I have hereunto set my hand.

JAMES E. GROSJEAN.

surface of the heel, the maximum wear-resisting properties of the material are utilized, and by arranging the cords, threads or fibers in the upper or superposed body, when used, so that they extend substantially parallel to the plane of the tread surface, secure anchorages for the attaching nails are provided which are capable of sustaining forces tending to pull the nail heads through the upper portion of the heel. Owing to the large proportion of textile material composing the heel, the weight of the heel is substantially less than that of the usual rubber heels, and in consequence they will be more comfortable, and they will cause less fatigue to the wearer.

I claim as my invention:—

1. A heel for boots and shoes comprising a tread-forming body made from re-claimed uncured tire material and composed of loose textile fibers and friction, most of the fibers extending in the same direction in said body and presenting their ends to the tread surface thereof, the friction being vulcanized and thus uniting the fibers elastically.

2. A heel for boots and shoes comprising a tread-forming body composed of unwoven textile fibers and high-grade highly elastic rubber, the fibers being distributed loosely through the body but extending mostly in the same direction therein and presenting their ends to the tread surface of the body, the fibers being bonded together elastically by the vulcanized rubber comprised in said body.

3. A heel for boots and shoes comprising a tread-forming body composed of unwoven gum-dipped textile threads and high-grade friction, the textile threads being distributed loosely in the body and extending mostly in the same direction therein and united elastically by said friction in the body whereby the fibers may accommodate themselves to compression of the body in the direction of the length of the fibers, the fibers pre-

senting their ends to the tread surface of the body.

4. A heel for boots and shoes comprising a lower tread-forming body and another body superposed thereon, each of said bodies being composed of unwoven textile threads distributed loosely through the respective body and extending mostly in the same direction therein and high-grade, highly elastic friction bonding together the threads in each body, the tread-forming body having a tread surface formed by the ends of the threads and the friction composing it, the threads in the tread-forming body being elastically connected by the friction therein and thus rendered capable of free movement relatively to one another to conform with compression of said body in the direction of the length of the threads by force applied to the tread surface.

5. A heel for boots and shoes comprising a body composed of gum-dipped frictioned unwoven textile fibers most of which extend in the same direction and are vulcanized together, said body having a tread surface the center of which tread surface is arched downwardly to produce a cushioning portion having a cavity above it.

6. A heel for boots and shoes comprising superposed bodies each composed of gum-dipped frictioned unwoven textile fibers most of which extend in the same direction in the respective bodies and are vulcanized together, one of said bodies forming a tread surface to which the fibers in said body are presented endwise, and the central portions of said bodies being arched downwardly, thus forming a cavity above such downwardly-arched portion and producing a cushioning action in said downwardly-arched portion.

In testimony whereof I have hereunto set my hand.

JAMES E. GROSJEAN.
